UNITED STATES PATENT OFFICE.

ARTHUR M. CRICHTON, OF UNIONTOWN, PENNSYLVANIA, ASSIGNOR TO MEASURED SERVICE METER COMPANY, A CORPORATION OF DELAWARE.

TELEPHONE METERING SYSTEM.

Application filed April 13, 1920. Serial No. 373,674.

To all whom it may concern:

Be it known that I, ARTHUR M. CRICHTON, a citizen of the United States, and a resident of Uniontown, in the county of Fayette and State of Pennsylvania, have invented 5 a new and useful Improvement in Telephone Metering Systems, of which the following is a specification.

My invention relates to telephone metering systems, and it has for its object to provide apparatus of the character designated whereby a meter installed in the calling subscriber's home must be partially actuated in order to call central, the actuation being 10 completed when the called subscriber removes the receiver from the hook, the last-named action sending a temporary impulse of excess voltage over the line to the calling subscriber's home.

20 The above and other objects will be pointed out more in detail in the subjoined description.

Referring to the accompanying drawing, Fig. 1 is a side view, partially in section and 25 partially in elevation, of a metering device constructed in accordance with my invention; Figs. 2, 3, and 4 are side and end views, respectively, of the device shown in Fig. 1, illustrating different phases in the operation 30 thereof; Fig. 5 is an assembly view of a telephone system embodying my invention and Figs. 6 and 7 are schematic views illustrating the calling subscriber's circuit with the receiver on and off, respectively.

35 In the operation of a telephone system, complaints are continually received from subscribers that they are being charged for calls which they never made and accordingly, the demand is arising for a metering 40 system whereby the calls made by a subscriber are recorded at his instrument so that no grounds for complaint can arise. A metering system of this character should be so arranged that the subscriber is unable to 45 call central without, at least partially, energizing the metering device and the consequent recordation of the call should be brought about by the response of the called subscriber.

50 With the above and other objects in view, I have devised a system whereby the calling

subscriber, by the manipulation of suitable means, throws a ground on one of the line wires and thereby calls the central office. Simultaneously the metering device is either 55 moved ahead one unit or is wound up as by the tightening of a spring for subsequent forward motion of one unit.

The response of the operator is in the usual manner and the calling and response 60 of the called subscriber are as usual. The removal of the receiver from the hook by the called subscriber, however, with the attendant production of a good current-carrying path between his two line wires initially 65 causes a transient or momentary flow of relatively high-voltage current over the calling subscriber's line, this current completing the energization of the metering device and the completion of the recording of an additional 70 unit or call therein.

Referring to the drawing for more detailed understanding of my invention, I will first of all describe the meter employed as an element in my system. A base member is 75 shown at 10 in Figs. 1 to 4 inclusive, bearing an upstanding support 11 carrying a counting device 12 of any usual or desired form. The base member 10 further carries an upstanding support 13 upon which is mounted 80 an electro magnet 14 provided with an armature 15 chamfered as shown at 16. A vertical tube 17 is centrally mounted on the base 10 between the supports 11 and 13 and carries a hollow plunger member 18, normally 85 urged upwardly by a spring 19.

The counting device 12 is operated by the oscillation of an arm 20 connected by a suitable link 21 to a lever 22 pivoted at 23.

A similar lever 24 is also mounted at 23, 90 directly behind the lever 22. The lever 24 engages the lower end of the plunger 18 and the lever 22 carries a pin 27 extending therethrough and terminating beneath a similar pin 29 carried by the lever 24 so that when 95 the plunger 18 is depressed, the levers 22 and 24 are both swung downwardly, as shown in Fig. 2, the action of the link 21 turning forward the counting device 12. The hook member 25 is pivoted at 26 and engages the 100 pin 27 on the lever 22 when the latter is in its lowermost position, as shown in Fig. 2, this

latch restraining the lever 22 from rising when the plunger 18 is forced out under the influence of the spring 19. A dog 28 is mounted beside the latch or hook 25 and is connected thereto as by a shaft in line with the pivot 26 so that when the hook 25 falls forward to engage the pin 27 the dog 28 is also permitted to swing forward toward the plunger 18. The lever 24 also carries a pin 29 and after the plunger 18 has been depressed to engage the hook 25 with the pin 27, the rise of the plunger 18 returns the lever 24 to its original position and the dog 28 swings under the pin 29, preventing a second depression of the plunger 18, until the pin 27 has been released from the hook 25.

The magnet 14, when energized, raises the armature and the notch 16 therein acts upon an extension 30 on the hook 25, swinging this hook in a clockwise direction and releasing the pin 27, so that the lever 22 may rise, permitting the swinging of the counting arm 20 to its original position and completing the counting act.

Two contact springs 31 and 32 are supported upon the member 11 by a suitable insulating mounting and the spring 32 is in the path of a cam 33 on the end of the lever 22 and also of a cam 34 on the end of the lever 24.

In the normal inoperative position, indicated in Fig. 1, the cam 33 maintains the spring 32 out of contact with the spring 31 and similarly, in the depressed position of the plunger illustrated in Fig. 2, the cam 34 maintains the spring 32 out of contact with spring 31. When however, the plunger 18 is released, after having been depressed, as shown in Fig. 3, the levers 22 and 24 are both in such positions that the spring 32 is permitted to engage the spring 31.

Having thus described the structure and the elements of the operation of the metering device employed by me attention is next directed to a system in which it is employed.

Referring to Fig. 5, the calling subscriber's apparatus is illustrated at A and comprises a receiver 35 mounted on a hook 36, a transmitter 37, an impedance coil 38, a condenser 39, a ringer 40, and a metering device having its parts designated as in Figs. 1 to 4 inclusive.

A hook switch is provided embodying springs 41 to 47 inclusive, the arrangement being such that with the receiver on the hook the springs 43, 44 and 45 are brought into mutual contact and the spring 41, 42, 46 and 47 are spread as indicated in Fig. 6. With the receiver off the hook, on the other hand, the springs 41, 42 and 43 are brought into mutual contact as are also the springs 46 and 47, the springs 44 and 45 moving out of contact with other springs. (Fig. 7.)

The spring 41 is connected through the impedance coil 38 to the tip or ground ter-

rninal of the subscriber's line, and the spring 42 is similarly connected through the transmitter 37 to the ring or battery side of the subscriber's line. The receiver 35 is connected between the springs 43 and 44 and the spring 44 is connected through the condenser 39 to the tip side of the subscriber's line. The ringer 40 is connected between the spring 45 and ground and the spring 46 is connected directly to ground. The spring 47 is connected through the elector magnet 14 of the metering device and through the contact springs thereof to the tip side of the subscriber's line.

Turning now to the central station apparatus, the usual answering jack equipment is indicated at 48, 49, 50, 51 and 52.

The cord circuit employed embodies a calling subscriber's supervisory lamp 53 and a called subscriber's supervisory lamp 54, the former being controlled by a relay 55 having an armature 56 and the latter being controlled by a relay 57 having an armature 58. In addition, a relay 59 is provided having an armature 60 with a front contact 61, an armature 62 having a front contact 63 and a back contact 64; and an armature 65 having a front contact 66 and a back contact 67; a relay 68 having an armature 69 with a front contact 70 and an armature 71 having a front contact 72; a relay 74 having an armature 75 with a front contact 76, an armature 77 with a front contact 78 and an armature 79 with a back contact 80; and a relay 81 having an armature 82 with a front contact 83 and a back contact 84 and an armature 85 having a front contact 86. The relay 81 is preferably of the quick-action type, for a purpose to be hereinafter pointed out, and the relay 74 is preferably of the slow-acting type, this action being produced for example by damping devices 87-87.

The tip 88 of the calling subscriber's plug is connected with the tip 89 of the called subscriber's plug through the condenser 90 and the members 71 and 72 and, in like manner, the ring 91 of the calling subscriber's plug is connected with the ring contact 92 of the called subscriber's plug through a condenser 93 for the provision of the usual type of talking circuit employed with cord circuits of the condenser type.

The lamp 53 is connected to the back contact 94 of the armature 56 and this armature is connected to the contact 61 of the relay 59, the corresponding armature 60 being grounded. The energizing coil of the relay 55 is grounded at one terminal and the remaining terminal is connected to the contact 84 of the relay 81, the corresponding armature 82 being connected to the armature 62 of the relay 59. The front contact 63 of this armature is connected to the tip side of the circuit and the back contact 64 is connected to an outer contact 95 of a 130

reverting call key 96. The front contact 83 of the armature 82 is connected to a relatively high-voltage battery grounded at 97 (such as a 48 volt trunking battery). The 5 coil of the relay 81 is connected to battery at 73 and the remaining terminal is connected to the armature 79 of the relay 74, the corresponding back contact 80 being connected to the armature 65 of the relay 10 59. The front contact 66 of this armature is connected to the front contact 98 of the relay 57 and the back contact 67 of the armature 65 is connected to a spring 99 in the key 96.

15 Switching key 96 is a recording key to operate the register on a reverting call, viz.: a calling party calling for another party on the same party-line. The operator necessarily will have to remove the calling subscriber's plug from the jack, and insert the called subscriber's plug to ring the desired party, and when he answers, she will have to press the key 96 to register the call, as the meter registers automatically only when 20 the calling subscriber's plug is in. I believe it would be better to call this key Re- 25 reverting call key.

The armature 85 of the relay 81 is grounded at 100 and the corresponding 30 front contact 86 is connected through the coil of the relay 74 to battery at 101, the contact 86 further being connected to the front contact 76 of the armature 75 in the relay 74. This armature 75 is connected to 35 the armature 58 of the relay 57 and is further connected with the contact member 102 in the key 96 and to the contact member 70 in the relay 68. The armature 69 of the relay 68 is grounded at 103.

40 The armature 77 of the relay 74 is connected to the spring 104 in the key switch 96 and is further connected to the tip side of the called subscriber's cord. The corresponding contact member 78 in the relay 74 is connected to the contact member 105 in the key switch 96 and through the coil of 45 the relay 57 to ground at 106.

The operating coil of the relay 68 is connected to battery at 107 and is connected to 50 the ring 92 of the called subscriber's plug.

The called subscriber's local circuit may be of the usual form indicated in C and embodying, for example, a transmitter 110, receiver 111, a condenser 112 for permitting 55 the flow of talking current through the receiver and an impedance device 113 to permit the flow of direct current through the transmitter, together with a bridging ringer 114 and a hook switch 115.

60 Having thus described the arrangement of a system embodying my invention, the operation thereof is as follows:

At the outset, the calling subscriber's receiver may be assumed to be on the hook, 65 so that his local circuit is as indicated in

Fig. 6. The calling subscriber desiring to signal "Central," removes the receiver from the hook, so that the circuit is established as in Fig. 7, and pushes the plunger 18. (It is not essential that the receiver be removed from the hook before plunger is depressed, the operation can be reversed with the same result) so as to actuate the recording mechanism leaving the meter in the condition as shown in Fig. 3, with the 70 springs 31 and 32 in contact allowing the current to flow from battery 115 through the winding of the line relay 48, through the back contact on the cut off relay 49, out on the ring side of the line to telephone, 80 through the transmitter 37, through the contacts 41-42 on the hook switch, through the impedance coil 38, through the closed contacts 31 and 32, and the winding 14, through closed contact on springs 46 and 47 85 to ground, energizing the relay 48 and lighting the line lamp signal 51. The current is insufficient however to bring up the armature 15 and therefore does not release the meter mechanism to complete the recordation of a call in the subscriber's meter.

The operator plugs into the answering jack in the ordinary manner, and the current flows from battery at 116 through the winding of the relay 59 and through the ring of 90 plug 91 to the answering jack 52. At this point the current divides (as the ring of the plug makes contact with the ring of the jack 52 and also with the ring of the jack 52 and also with the sleeve of the jack) part 100 of the current flowing through the sleeve contact, through the winding of the cut-off relay 49 to ground, the remainder flowing thru the sleeve spring, out over the sleeve side of line, through the telephone, returning on the tip side of the line, through the tip spring, to the tip of the answering plug 88. This closes the contacts 62-63 on the relay 59 and provides a path through contacts 82-84 on the relay 81 through the 105 winding of the relay 55 to ground, energizing this relay and opening contact between 56 and 94, preventing the lamp 53 from lighting while the receiver 35 is off the hook.

Having ascertained the desired party, the operator plugs in the jack with the calling plug and rings the called subscriber in the usual manner. The insertion of the calling plug permits current to flow from battery at 107, through the winding 68, through the sleeve of the calling plug 92, to the sleeve spring of the jack, through the winding of the cut-off relay to ground, energizing the relay 68, closing the contact 71 on 72 and also 69 on 70, allowing battery to flow 110 through the lamp 54, armature 58 and armature 69 and contact 70 to ground at 103, lighting the supervisory lamp.

When the called party answers the ring at his telephone by removing the receiver 115

from the hook, he eventually establishes contact between the armature 82 and the contact 83, sending an impulse of high voltage current out to the calling subscriber's meter and completing the recordation of the call. The closure of the contacts in the hook switch allows current flow from 107 through 68 and 92, dividing at the jack, part flowing through the winding of the cut-off relay, 10 as already explained, and the other part through the hook switch etc. in the telephone and returning on the tip side of the line to the tip of the calling plug 89, the armature 71, the contact 72, the contacts 104—105 the winding of relay 57 and to ground at 106, energizing the relay 57, breaking the contacts 99—58 not only extinguishing the calling supervisory lamp 54, as just mentioned, but the closing of contact on the member 20 98 by the armature 58 permits battery flow from 73 through the winding of the relay 81, the contacts 79 and 80, the contacts 65 and 66, the contacts 98 and 58 and the contacts 70 and 69 to ground at 103, energizing the relay 81, which is preferably of the quick-acting type. The armature 82 is accordingly moved down, breaking contact with 84. At the same time, contact is established between the armature 82 and the contact 83 throwing 48-volt current from the battery grounded at 97 out through the members 82 and 83 and members 62 and 63 to the tip side of the cord circuit, whence it flows over the calling subscriber's line, 30 through the contacts 31 and 32 and the winding of the electro magnet 14 of the meter to ground through the spring 46, thus releasing the lever 22 from the hook 25 and restoring the meter to its original condition 40 opening contact at 31—32 with the exception that an additional call has been irrevocably recorded.

The energization of the quick-acting relay 81 also closes the armature 85 on the contact 86 so that current flows from the battery at 101 through the winding of the relay 74 and to ground at 100, energizing the relay 74, which is preferably sluggish in action, so as to permit the flow of 48-volt current to 50 the calling subscriber's meter for an appreciable period of time. The energization of the relay 74, however, draws up the armature 79, breaking contact with the member 80 and thus de-energizing the relay 81, 55 stopping the flow of 48-volt current. The closure of the armature 75 on the contact 76 locks the relay 74 in the closed position and the contact of the armature 77 with the member 78 establishes a path for the flow of current through the called subscriber's line, it being well understood that the talking current between the subscribers traverses the condensers 90 and 93 in the usual manner.

Various other details on the operation of 65 the system will be understood by those

skilled in the art, but as they constitute no part of the present invention, it is deemed unnecessary to needlessly encumber the disclosure therewith.

Assume now that the desired party does 70 not answer. A 48-volt releasing impulse does not come over the calling subscriber's line and his meter remains in the condition shown in Fig. 3. The plunger 18 cannot be depressed because of the action of the dog 28, 75 but central can be called because of the contact between the springs 31 and 32. The next succeeding call may therefore be made without an additional depression of the plunger 18 and without the recordation of 80 an additional unit in the mounting mechanism. Thus the total number of calls recorded is determined by the actual number of completed calls.

If by mistake the operator should connect 85 the calling subscriber to the wrong number, when that wrong party answers the ring at his telephone, by removing the receiver from the hook, part of the current would return on the tip side of the line, eventually energizing the relay 81, sending current to the meter recording the call, and at the same time closing contacts 85—86 on the relay 81, allowing current to flow from 101 through the winding 74 through the contacts 85 and 86, energizing the relay 74. This closes the contacts 75—76, locking the relay 74 and at the same time opens the contacts 79—80, de-energizing the relay 81 and preventing it from working again as long as 74 is locked, 90 so that when the calling subscriber ascertains he has the wrong number and signals central by moving his receiver hook up and down to flash the supervisory lamp 53, should he again push the button, an additional call will not be registered. 100

While I have shown my invention in but one form, it will be obvious to those skilled in the art that it is not so limited, but is susceptible of various other changes and 110 modifications, without departing from the spirit thereof and I desire, therefore, that only such limitations shall be placed thereupon as are imposed by the prior art or as are specifically set forth in the appended 115 claims.

What I claim is:—

1. In a telephone system, a metering device at the calling subscriber's station responsive to a uni-directional voltage across 120 the subscriber's line in excess of the normal talking voltage and initially under the calling subscriber's control, and means for temporarily impressing an excess voltage thereupon when the called subscriber removes the receiver from the hook. 125

2. In a telephone system, an electro-responsive metering device at the calling subscriber's station, normally open-circuited, means independent of the receiver hook 130

- whereby said device may be close-circuited by the calling subscriber, in which condition it is responsive to voltage across the line, and means whereby the removal of the receiver from the hook by the called subscriber impresses a temporary voltage upon said metering device adapted for the operation thereof. 5
3. In a telephone system, an electro-responsive metering device, normally open-circuited, means independent of the receiver hook whereby said device may be close-circuited by the calling subscriber for the calling of the operator, in which condition it is responsive to voltage across the line in excess of the normal talking voltage, and means whereby the removal of the receiver from the hook by the called subscriber impresses a temporary excess voltage upon the metering device for the operation thereof. 10
4. A telephone metering device comprising a counting mechanism, an electro-magnet, normally open switching means, and manually operable means for partially operating said counting mechanism and for simultaneously closing said switching means, and connections whereby subsequent energization of said magnet through said switching means completes the operation of said counting mechanism. 15
5. A telephone metering device comprising a counting mechanism, an electro-magnet, switching means, and manually operable means for partially operating said counting mechanism and for simultaneously closing said switching means, and connections whereby subsequent energization of said magnet through said switching means completes the operation of said counting mechanism, and opens said switching means. 20
6. In a telephone metering device, the combination with counting mechanism operable by an oscillatable lever, of a manually depressible plunger adapted to move said lever in one direction when depressed, locking means for preventing the return motion of said lever upon the recession of said plunger and an electro-responsive releasing device disassociated with the talking circuit for said locking means. 25
7. In a telephone metering device, the combination with switching means and a counting mechanism operable by an oscillatable lever, of a manually depressible plunger adapted to move said lever in one direction when depressed and to close said switching means, locking means for preventing the return motion of said lever upon the recession of said plunger, an electro-responsive releasing device for said locking means and adapted to be energized through said switching means, the release of said locking device also opening said switching means. 30
8. In a telephone system embodying two sets of subscriber's equipment, a central provided with a relatively low voltage current source and a relatively high voltage current source, and a metering device at one subscriber's station, the method of operation which comprises initially operating said metering device by a calling subscriber to partially register a call, automatically completing the registration of said call by means of a momentary impulse of high voltage current over the calling subscriber's line when the called subscriber responds, and thereafter conversing with relatively low-voltage current. 70
9. In a telephone system embodying two sets of subscriber's equipment, a central provided with a source of uni-directional current, and a metering device at one subscriber's station, the method of operation which comprises initially energizing said metering device by the calling subscriber to partially register a call and automatically completing the registration of said call by an impulse of current from said source upon the response of the called subscriber. 75
10. In a telephone system, an electro-responsive metering device at the calling subscriber's station, responsive only to a voltage in excess of the normal talking voltage and initially under the calling subscriber's control, a high voltage source at the central, a quick-acting relay and a slow-acting relay at the central, and means whereby, upon the called subscriber raising the hook, said quick acting relay closes a circuit whereby said high voltage source is connected to the calling subscriber's line for the operation of said metering device and means whereby said slow-acting relay operates an instant later to cut off said current flow. 80
11. In a telephone metering system involving the flow of current in one direction only over the subscriber's line, the combination with means whereby the calling subscriber must partially register a call before establishing communication with the operator, of means whereby the registration of the call is completed by the called subscriber without the intervention of the operator. 85
12. In a telephone metering system involving the flow of current only in one direction over a subscriber's line, the combination with a metering device at the calling subscriber's station and connected in a circuit to ground, of means whereby the calling subscriber must partially register a call before establishing communication with the operator, and means whereby the registration of the call is completed and said ground connection is broken by the called subscriber without the intervention of the operator. 90
13. In a telephone metering system involving the flow of current only in one direction over a subscriber's line, the combination with a metering device at the calling subscriber's station, of means whereby the calling subscriber must partially register a call and automatically completing the registration of said call by means of a momentary impulse of high voltage current over the calling subscriber's line when the called subscriber responds, and thereafter conversing with relatively low-voltage current. 95
14. In a telephone metering system involving the flow of current only in one direction over a subscriber's line, the combination with a metering device at the calling subscriber's station and connected in a circuit to ground, of means whereby the calling subscriber must partially register a call before establishing communication with the operator, and means whereby the registration of the call is completed and said ground connection is broken by the called subscriber without the intervention of the operator. 100
15. In a telephone metering system involving the flow of current only in one direction over a subscriber's line, the combination with a metering device at the calling subscriber's station and connected in a circuit to ground, of means whereby the calling subscriber must partially register a call before establishing communication with the operator, and means whereby the registration of the call is completed and said ground connection is broken by the called subscriber without the intervention of the operator. 105
16. In a telephone metering system involving the flow of current only in one direction over a subscriber's line, the combination with a metering device at the calling subscriber's station, of means whereby the calling subscriber must partially register a call before establishing communication with the operator, and means whereby the registration of the call is completed and said ground connection is broken by the called subscriber without the intervention of the operator. 110
17. In a telephone metering system involving the flow of current only in one direction over a subscriber's line, the combination with a metering device at the calling subscriber's station and connected in a circuit to ground, of means whereby the calling subscriber must partially register a call before establishing communication with the operator, and means whereby the registration of the call is completed and said ground connection is broken by the called subscriber without the intervention of the operator. 115
18. In a telephone metering system involving the flow of current only in one direction over a subscriber's line, the combination with a metering device at the calling subscriber's station, of means whereby the calling subscriber must partially register a call before establishing communication with the operator, and means whereby the registration of the call is completed and said ground connection is broken by the called subscriber without the intervention of the operator. 120
19. In a telephone metering system involving the flow of current only in one direction over a subscriber's line, the combination with a metering device at the calling subscriber's station, of means whereby the calling subscriber must partially register a call before establishing communication with the operator, and means whereby the registration of the call is completed and said ground connection is broken by the called subscriber without the intervention of the operator. 125
20. In a telephone metering system involving the flow of current only in one direction over a subscriber's line, the combination with a metering device at the calling subscriber's station, of means whereby the calling subscriber must partially register a call and automatically completing the registration of said call by means of a momentary impulse of high voltage current over the calling subscriber's line when the called subscriber responds, and thereafter conversing with relatively low-voltage current. 130

ister a call before establishing communication with the operator, said means remaining in the partially operated position upon the failure of the operator to secure the called subscriber, whereby the calling subscriber may subsequently call the operator without further initial actuation of his metering device.

In testimony whereof, I have hereunto subscribed my name this 9th day of April, 1920.

ARTHUR M. CRICHTON.
